(57) **CLAIM**

The ornamental design for an exercise bar, as shown and described.

DESCRIPTION

FIG. 1 is a front, top, right perspective view of an exercise bar showing our new design;

FIG. 2 is a rear, bottom, left view thereof;

FIG. 3 is a left side view thereof;

FIG. 4 is a front view thereof;

FIG. 5 is a right side view thereof;

FIG. 6 is a rear view thereof;

FIG. 7 is a top view thereof;

FIG. 8 is a bottom view thereof;

FIG. 9 is a front, top, right perspective view of a second embodiment of an exercise bar;

FIG. 10 is a rear, bottom, left view of the second embodiment thereof;

FIG. 11 is a left side view of the second embodiment thereof;

FIG. 12 is a front view of the second embodiment thereof;

FIG. 13 is a right side view of the second embodiment thereof;

FIG. 14 is a rear view of the second embodiment thereof;

FIG. 15 is a top view of the second embodiment thereof;

and,

FIG. 16 is a bottom view of the second embodiment thereof. The broken lines shown in the drawings illustrate structure or features that form no part of the claimed design.

For greater certainty, the portions illustrated with broken lines include grip portions for a handle of the device in which the grip portion and the pattern depicted on the grip portion form no part of the claimed design.

The claimed design is shown with a symbolic break in its length. The appearance of any portion of the article between the break lines forms no part of the claimed design.
